UNITED STATES PATENT OFFICE.

GEORGE E. MARLATT, OF PASADENA, CALIFORNIA.

TYPOGRAPHICAL SLUG-CASTING MACHINE.

* Application filed October 5, 1926, Serial No. 139,717. Renewed July 5, 1928.

- My invention relates to machines of the kind in which circulating matrices are released from a magazine by keyboard means and assembled into a line by groups representing words, the words being separated by expansible spacers (usually designated space-bands), the line being then transferred to the face of a mold in which a type-slug is cast against the assembled matrices and spacers. The final movement of the assembled line to its position in front of the mold is in a vertical direction in and with a movable organ commonly known as the first elevator. The matrices are provided with mold-engaging lugs which enter a selected and predetermined one or more of grooves in the face of the mold, the engagement of the lugs with the grooves being incidental to the movement of the mold against the line of matrices and spacers. When thus engaged, the elevator moves slightly upward in order to insure vertical alinement of the matrices by pressing their mold-engaging lugs against either a rib which separates the grooves in the mold or against the rib which separates the highest groove from the mold casting-slot. While thus alined the wedge part of the expansible spacers is driven up between the words composing the line, causing the line to be expanded to fill the space between a pair of casting jaws in which it is confined endwise while in front of the mold. Heretofore the distance which the spacer wedges may be driven upward has been a fixed distance determined by contact of the wedge driver with the under edge of the casting jaws. This fixed and limited movement of the driver has a disadvantage due to the fact that when the matrices are engaged with the upper groove in the mold the spacers do not have their full expansive effect, and this is particularly objectionable for the reason that the largest matrices such as require wide spacing between words are of necessity made to engage the upper groove. A feature of my present improvements is designed to eliminate the above-noted objectionable limitation by rendering the spacer driver movable to varying distances according to the position of the matrices relative to the mold. A closely related feature is concerned with means for preventing the matrices from being inadvertently presented to the mold at a higher level than is provided for as determined by the position of the highest groove on the mold; also, I provide that this feature may co-operate with a mold having three positioning grooves, the usual number thereof being but two. The manner of attaining the objectives mentioned is illustrated in the accompanying drawings, in which—
- Fig. 1 is a front elevation of a portion of a slug-casting machine of the linotype class, showing my improvements applied thereto; Fig. 2 is a plan projection of Fig. 1, showing the path of the assembled lines from the assembler to the first elevator, and the relation thereto of my improved devices for insuring proper alinement of the matrices with the mold grooves, with the primary alining stop inoperative and the secondary alining stop operative; Fig. 3 is a view similar to Fig. 2, but showing the primary alining stop operative and the secondary alining stop inoperative; Fig. 4 is a view similar to Fig. 2, showing both alining stops in inoperative position as a result of assembling the matrices at a conflicting level in the assembler. Figs. 5, 6 and 7 show matrices at three different levels in front of the mold, the levels thereof being determined by the size of their letter-characters. These three views also show the spacer wedges as driven from and to three different levels according to the level of the associated matrices.
- Fig. 8 shows a detail in the several positions to and from which it is shiftable; Fig. 9 is a perspective of a fragment of the first elevator, showing a detail of my spacer-driver control applied thereto. Fig. 10 is a section on the line 3—3 of Fig. 1, showing the co-operative relation of my improvements one with the other; Fig. 11 is a view as from the rear of Fig. 1. The matrices X may be assembled at either of two levels in the assembler A, according to whether their lower lugs X¹ are supported on or below an upper assembling rail A¹; or, part of a line of matrices may be assembled on the rail A¹ and the other part at the lower level. If the mold M is provided with three grooves M¹, M², M³ matrices assembled at the upper level will be presented to the mold with their lower lugs in engagement with the middle groove as indicated in Fig. 11, unless one of the first elevator aligning-stops G or H is in operative position between adjustment screws E¹, E² and the frame F on which the first elevator is movable, in which case the matrices assembled at the upper level will be presented for engagement with the upper groove M³. But if both alining stops

G, H are in operative position and the matrices are presented to the mold after having been assembled at the upper level, then their lower lugs X¹ would, in the absence of a preventative, be struck by the mold-slot lip M⁴ when the mold advances towards the matrices, and damage would result to the matrices and a leakage of the molten metal would result because of the abnormal occurrence.

10 In order to prevent such an abnormal occurrence I provide a lever D mounted on the top of the front wall of the intermediate channel C in a plane which will permit the upper lugs X² of the matrices to pass thereunder provided they have been assembled at the lower level in the assembler A. If, however, the matrices have been assembled at the upper level and transferred to the intermediate channel when the assembler is elevated to align therewith, then the matrices will engage the inner edge of the lever D and force it out of their channel C. For the purpose of such engagement the edge of the lever, when in operative position recedes towards its pivot D¹ to a point outside the path of the matrices. When thus forced out of the channel C the lever D serves to cause the alining stops G, H (one or both, optionally) to move from operative position so that the elevator E may present the matrices to the mold in a safe position. In order that the lever D may thus serve, I provide as follows:

One of the alining stops G, which may be considered the primary stop for the reason that it is most convenient to the operator, is mounted for pivotal movement with a shaft F³ having a pivotal and sliding bearing in brackets F⁵, F⁶ secured to the frame F. The 40 alining stop G is swung to operative position against the resistance of a spring F⁴ and is latched in operative position in an undercut shoulder F⁷ on the bracket F⁶, the spring F⁴ serving also to keep the stop G in latched position. Operative connection between the stop G and lever D is established by means of a bail-like lever I hingedly mounted by means of brackets I¹, I² on the front wall of the channel C. The upper arm of this bail-lever enters a horizontal bore D² in a vertical shoulder of the lever D for movement therewith; the lower arm of the bail-lever terminates in line with the pivot of the alining stop G. When the lever D is forced out of the channel C by the matrices as explained, the lower arm of the bail-lever I will simultaneously force the alining stop G from engagement with the latching shoulder F⁷ and the spring F⁴ will cause the stop G to swing to inoperative position, all as illustrated in Fig. 4. In machines employing only matrices of the two-letter kind the middle M² and upper M³ mold grooves will suffice for engaging such matrices with the mold and a secondary alinement stop will

not be required; and in machines employing the matrices in three positions the primary stop G need not be automatically retractable as above described, for only when the two stops are employed together would the abnormal condition be liable to result; and since in certain circumstances it may be desirable to have the matrices in raised position in the channel C while one stop G remains operative, it may therefore be found desirable to bend the lower arm of the bail-lever I to non-operative position or even to eliminate the bail-lever on machines employing the two alinement stops.

The secondary alinement stop H is carried by the elevator E, being secured to the inner end of a stud H¹ which is longitudinally slidible in the elevator head, and is provided with an operating knob H² at its outer end. A spring H³ serves to press the stop H upward against the adjustment screws E¹, E² when the stop is operative, and when it is turned to inoperative position the same spring presses it upward between the adjustment screws and against the elevator head. The knob H² has a notch H⁴ which is engaged by the end of a centrally-pivoted trigger-latch J when the stop is operative. When the latch J is disengaged from the notch H⁴ a spring H⁵ serves to move the stop H to inoperative position. If the lever D is forced out of the channel C in the manner explained, the free end thereof will be beneath the free end of the latch J and when the elevator E descends the latch will strike the lever and rock on its pivot J¹, thus freeing the knob H² and causing the stop H to move to inoperative position as in Fig. 4. When the latch is thus freed from the notch H⁴ it is pulled backward by means of a spring J² so that its free end will not engage the lever D when the elevator E ascends. For this purpose the pivot J¹ is rigid in the latch J and moves in the slot J² in which it has a bearing. Vertical movement of the free end of the lever D is prevented by means of a pin C¹ and slot D³ connection.

In Figs. 5, 6 and 7 three spacers S are shown as driven up their full expansive distance, the sleeve part remaining vertically stationary in the first elevator and the wedge being the driven part. In Fig. 7 is also shown a spacer with the wedge in normal position. It will be apparent that if the wedge driver K were permitted to rise as far as the end of the spacer in Fig. 5 while the spacer remained held in the lower position shown in Fig. 6, it would cause damage by striking the matrices and the thin lower edge of the spacer sleeve S¹; likewise, if the driver were adjusted to permit it to rise to the position indicated in Fig. 6, damage would ensue if the spacers were held in the position shown in Fig. 7. It is for this reason that the driving distance of the driver K has heretofore been limited

with regard to matrices and spacers in the lowest position in front of the mold, and this is particularly objectionable if the matrices have three casting positions as contemplated by this and other inventions, and to a less degree is objectionable in connection with two casting positions. This is because matrices having large characters require wide spacing and such matrices are of necessity held at the higher casting levels as indicated in Figs. 5 and 6; also, matrices having two or three small characters thereon for selective use should receive the same spacing regardless of their position relative to the mold. In order that the desired result may be attained I provide as follows:

A banking bar L having sets of stepped and recessed shoulders L^1 , L^2 , L^3 is itself banked beneath protruding parts F^1 of the frame F and is supported and guided for longitudinal adjustment in suitably notched straps L^4 fastened to the frame F. The driver K is supported in usual manner on the ends of the driving rods K^1 , K^2 which are actuated by levers under control of springs and cams (not shown) all in the well known manner. In their driving action the rods K^1 , K^2 are spring actuated in order that they may rise varying distances according to the required expansion of the spacers as determined by the degree of looseness in the line of matrices between the casing jaws P, Q; hence, the driver K rises its extreme distance only in the event of a loose line of matrices. The shoulders L^1 , L^2 , L^3 are the same vertical distance apart as the grooves M^1 , M^2 , M^3 in the mold. To co-operate with these shoulders each driving rod is provided with a tapered shoulder K^3 . If the lowest shoulder L^1 is above the tapered shoulder K^3 the movement of the driver is thereby limited to co-operate with the spacers when in their lowest position as in Fig. 7; in like manner the middle shoulder L^2 co-operates with the middle groove M^2 in the mold, and the highest shoulder L^3 co-operates with the highest groove M^3 in the mold. In order that the appropriate shoulders on the bar L may be above the tapered shoulders K^3 when the elevator E descends to a predetermined one of its three levels, the bar L is under control of a pivoted lever N having a crank arm N^1 which engages a groove O running vertically on the back of the elevator E except that its upper end is shaped as a cam O^1 to impart movement to the banking bar K when the elevator approaches its lower level. If the elevator descends its extreme distance by reason of the alinement stops G, H being non-operative then the cam-groove O^1 (Fig. 9) will deflect the lever N a corresponding distance and place the bar K in the position shown in Fig. 11 and in the upper position of Fig. 8. If a single alinement stop is operative beneath the elevator head, then the bar L will occupy

its middle position as shown in the middle of Fig. 8; and with both alinement stops operative as in Fig. 10 the bar will occupy the position shown at the bottom of Fig. 8 and the driver K may rise to its highest level with the tapered shoulders K^3 engaging the highest shoulders L^3 on the bar L. With the driving distance of the driver K thus regulated it will be apparent that the spacers may have their full range of expansion regardless of the level at which they are held by the first elevator as determined by the use or omission of one or both of the alinement stops.

Having thus described my improvements, their operation and the advantages of their use, what I claim as new and desire to secure by Letters Patent, is:

1. In a typographical slug-casting machine in combination with an assembler in which matrices may be assembled at selective levels, a mold, a vertically movable carrier for presenting a line of matrices to said mold at selective levels, an intermediate channel through which said line of matrices is conveyed from said assembler to a selective level in said carrier, and an alinement stop for limiting the descent of said carrier in front of said mold, means operable by the movement of said line of matrices through said intermediate channel whereby said alinement stop will be caused to move from its operative position in the event that said line of matrices is presented to said carrier at a level in conflict with the level at which said line of matrices should be presented to said mold as determined by said alinement stop when in operative position.

2. In a typographical slug-casting machine in combination with a mold having grooves for engaging matrices at selected levels, an elevator for presenting said matrices to said mold at a predetermined level, an alinement stop carried by said elevator to and from a position in front of said mold for controlling the level at which said matrices may be presented to said mold, an assembler in which matrices may be assembled at selected levels, and an intermediate channel through which said matrices are conveyed from said assembler to said elevator, means whereby said alinement stop is automatically rendered non-effective in the event that said matrices are assembled and transferred at a level in conflict therewith, said means being an element operable in said intermediate channel and capable of being displaced by said matrices when in said channel at a conflicting level, and an element on said elevator for locking said alinement stop in effective position, whereby the descent of said elevator will cause said locking element to release said alinement stop by contact thereof with said intermediate channel element when moved by the matrices in said intermediate channel, thus moving said alinement stop to non-effective position.

3. A combination and structure as set forth in claim 2, and including also a stationary frame on which the elevator therein recited is mounted, an additional alinement stop 5 mounted on said frame for use in co-operation with the alinement stop carried by said elevator, and means whereby both of said alinement stops may be rendered non-effective when the movable element associated with 10 the intermediate channel is displaced by the matrices in said channel.

4. In a typographical slug-casting machine in combination, a mold having matrix engaging grooves, matrices capable of engaging a

selected one of said grooves, a matrix elevator capable of being stopped at different levels for presenting said matrices to a selected groove in said mold, expansible spacers carried by said elevator in common with said matrices, a driver for expanding said spacers, and means controlled by said elevator whereby the extent of movement of said driver will be limited to conform with the level at which 15 said matrices are held by said elevator in relation to said mold. 20

Signed at Pasadena, Los Angeles County, California, this 28th day of September 1926.

GEORGE E. MARLATT.
